UNITED STATES PATENT OFFICE.

WALTER C. ELY, OF TERRE HAUTE, INDIANA.

LINING FOR FURNACES.

1,284,880.

Specification of Letters Patent. Patented Nov. 12, 1918.

Application filed February 5, 1916. Serial No. 76,319.

To all whom it may concern:

Be it known that I, WALTER C. ELY, a citizen of the United States, residing at Terre Haute, in the county of Vigo and State of Indiana, have invented certain new and useful Improvements in Linings for Furnaces, of which the following is a specification.

My invention relates to linings for furnaces and the like, and has for its object the provision of a cellular lining for metal working and other furnaces, which is adapted to take up molten material from the interior of the furnace and cause this molten material to be cooled in a manner to vary the thickness of the lining in accordance with the heat of the furnace. Other objects will appear hereinafter.

An embodiment of my invention is illustrated in the accompanying drawings forming a part of this specification, and in which—

Figure 1 is an end view of a rotary metal working furnace equipped with a lining made in accordance with my invention;

Fig. 2 is an enlarged fragmental section of one of the walls showing my lining after having been in use;

Fig. 3 is a longitudinal section of a rotary metal working furnace equipped with my lining and positioned between a fire-box and a chimney set up for use;

Fig. 4 is a view in perspective of two end sections and a circular lining therefor, of the furnace;

Fig. 5 is an elevation of one of the end sections of the furnace;

Fig. 6 is a top view of the part shown in Fig. 5, and

Fig. 7 is a view taken on line 7—7 of Fig. 5.

Referring more particularly to the drawings, I have shown a rotary type of metal working furnace mounted in operative position between a fire-box 10, and a chimney 11 (see Fig. 3), portions only of the fire-box and chimney being shown. The kind and form of furnace may be varied when so desired, as will be apparent from the description herein.

The furnace illustrated in the drawings comprises a rotatable chamber connected to spaced-apart circular bearing rings 12 mounted on rollers 13, which are journaled in the supporting pedestals 14. A shaft 15

forms the axle of two of the rollers 13. By means of the pulley 16, keyed to the shaft 15, power may be applied to effect the rotation of the bearing rings 12 and the parts connected thereto.

The rotatable furnace may be of any suitable shape or size, but I prefer to construct the same with four square or rectangular flat side walls 17, 18, 19 and 20—21, and with two end walls 22 and 23. The preferred construction with reference to the means for fastening the side and end walls together is similar to that illustrated in the United States Patent No. 1,155,410, granted to me on October 5, 1915, for an improvement in metal working furnaces.

In the accompanying drawings, I have shown each of the side walls as composed of a metallic plate with cellular metallic blocks 25 locked to the interior surfaces of said plates to form a lining for the rotatable furnace. These metallic blocks 25 are preferably composed of cast iron when the furnace is used for heating or working iron or steel. The outside plate of each of the side walls 17, 18, 19 and 20 is substantially rectangular and flat and is provided with a flange 26, as shown in Fig. 1. The flange 26 of each side wall plate extends around three of its sides or edges to a height substantially equal to the thickness 80 of the blocks 25.

The inner surface of each side wall plate is provided with V-shaped ribs 27 to provide dove-tail connections therebetween, which serve to lock the blocks in position on the plates. The dove-tail grooves on the inner surfaces of the side wall plates extend transversely; therefore, after the blocks 25 are slid into position, the side wall plates are secured together to lock the blocks 25 against transverse movement along the dove-tail grooves. The side wall 19 is secured to the side wall 17 by bolts 28 passing through ears 29, as shown in Fig. 1. In a similar manner, the side wall 18 is secured to the side wall 19 by means of the bolts 31 passing through the ears 32. The side walls 17 and 18 are secured to the side wall 20—21 by means of a similar construction.

The wall portion 21 is pivoted to the wall portion 20 by hinge members 33 to provide a door for the rotatable furnace, through which the material may be charged into and discharged from the furnace. The door 21 is preferably mounted and operated as set 111

forth in my aforesaid Patent No. 1,155,410, granted October 5, 1915, in which door-operating mechanism on a rotatable furnace, as well as the particular means for mounting the door shown in Fig. 1, is not only described but also claimed. I wish it to be understood, however, that the present invention as defined by the appended claims may have a general application, and is not to be understood as restricted to any particular type of furnace nor to a furnace of any particular shape.

The side walls 17 and 18 are shown in Fig. 1 as provided with ears 34, which are secured to ears 35 extending radially inwardly from the bearing rings 12. The ears 34 are secured to the ears 35 by means of bolts 36, so that the bearing rings may be rigidly connected to the rotating furnace.

By referring to Fig. 3, it will be seen that the metal lining blocks 25 are each provided with perforated cross plates 37, dividing the interior of the blocks into small compartments 38. Each of the side wall plates is also provided with perforations 40, which communicate with the small compartments formed by the wedge members 60 which fit in the dove-tail grooves. It will thus be seen that the interior compartments 38 of each of the metal blocks 25 is in communication with the outside atmosphere through the perforations 39 and 40, as shown in Fig. 3. Each metal block at the portion exposed to the heat in the rotatable furnace is initially entirely closed but after the initial charge, for instance, cinder, ore or scrap iron, is introduced into the furnace and the heat from the fire-box 10 permitted to pass through the interior of the furnace proper while the latter is being rotated, the exposed middle portion of each of the blocks will be melted at a predetermined temperature and the molten or plastic slag or cinder from the charge will immediately flow into the inner compartments 38, and thence to a smaller extent through the perforations 39 into the next compartment 38. As soon as the slag or cinder comes in contact with the air in the compartments 38, it tends to harden, but if the heat is sufficiently intense in the interior of the rotatable furnace, the slag or cinder may not solidify sufficiently to stop its flowing until it reaches the second or third compartment in each of the metal blocks, as illustrated in Fig. 2, wherein 61 designates the slag or cinder which automatically combines with the unmelted portions of the metal devices 25 to form a refractory lining for the rotating furnace proper.

It should also be noted that the chilling of the slag or cinder in the compartments of the metallic block by means of the atmospheric air in the compartments serves as an automatic regulation of the thickness of the refractory lining. The refractory lining

will, therefore, automatically assume a thickness in accordance with the degree of heat insulation required. At comparatively low temperatures, it may be sufficient that the slag or cinder merely fills the interior compartments and partly the intermediate compartments, whereas, if the heat is at a maximum, the slag or cinder will not be sufficiently chilled to stop it from flowing until all the compartments are partially filled with slag to the extent shown in Fig. 2. After that condition is reached, the chilling effect, due to the confined air pockets and the outside atmosphere entering through the perforations 40 remaining open, will be sufficient to maintain the slag or cinder combined with the remaining portions of the metallic blocks to form a proper refractory lining against the maximum temperature to be used in the rotating furnace. Any tendency for the predetermined maximum temperature to be exceeded will be checked by radiation through the refractory lining and the metallic blocks 25 and the side walls of the rotating furnace. However, within the range of temperatures used in practice for the working of scrap iron, as disclosed in my Patents Nos. 1,155,409 and 1,155,410, granted on October 5, 1915, the slag or cinder will be sufficiently chilled from the outside atmosphere entering the compartments of the blocks 25 through the perforations therein, to maintain a solid refractory lining, as illustrated in Fig. 2, during the continuous rotation of the furnace under practical conditions.

The same principle of automatically forming a refractory lining for exposed metal portions on the interior of a rotating furnace may also be applied to the end walls 22 and 23. In Fig. 1, I have illustrated the end wall 23 as being composed of eight hollow metallic blocks each of a general triangular shape. In each block 41 of the end walls there are a plurality of partitions 42, as shown in Figs. 6 and 7, which are preferably integral with the block itself. The partitions 42 divide the block 41 into compartments 43, which are in communication with each other through the perforations 44 in the partitions 42. The inside wall of each block 41 is entirely closed but the outside wall is provided with a plurality of small perforations 45 and an enlarged perforation 45'. While I have shown the end walls as being composed of eight hollow blocks 41, it should be understood that there may be any desired number. This is also true with respect to the blocks 25 secured to the inner surfaces of the side walls. Although I prefer to provide a plurality of small blocks for convenience in assembling and for removal for repairs, the blocks 25 may be increased to such a size that there will be only one for each side wall with the

cells reduced to the small number of three, if desired. It is preferred, however, to have a multiplicity of cells so as to reinforce the refractory lining after being formed, thus enabling the lining to withstand the repeated blows and abrasion from the metal while it is being heated and worked, as described in my aforesaid patents.

The blocks 41 of the end walls may be secured to the side walls by means of screws 46 which pass through ears 46' on the edges of the flanges 26 of the side walls, as shown in Fig. 1. This is true of all the blocks except those which are opposite the door 21, which are secured to the next adjacent blocks by means of bolts 47 passing through ears 48 on adjacent edges of the blocks, as shown in Figs. 1 and 4.

Through the central portion of each of the ends 22 and 23 are large circular openings 49, which provide a communication with the fire box 10 and the chimney 11. In order to protect the edges of the blocks 41 adjacent the openings 49, I provide lining blocks 50 of refractory material. These blocks 50 are held in position by ribs 52 on the blocks 41, which engage grooves 51 in the blocks 50.

Inasmuch as the interior of the furnace 30 has flat walls, the inner ends of the hollow blocks 41 will be exposed to the interior heat of the furnace over the area bounded by the dotted lines 62 in Fig. 4. Fig. 4 represents two blocks 41 adjacent each other 35 at one corner of the furnace, and shows that notwithstanding the refractory lining 50 a considerable area of the inner metallic portion of the blocks 41 will be exposed directly to the interior heat of the furnace. The 40 operation with respect to the automatic formation of a refractory lining for the end walls is substantially the same as that hereinbefore described with respect to the formation of the refractory lining for the 45 side walls. The molten slag or cinder will enter the compartments 43 after the exposed metal portion has been melted, and the slag will flow through the perforation 44 and partially fill the compartments 43, until the 50 chilling of the air therein and of the outside atmosphere is sufficient to solidify the slag or cinder and form the refractory lining desired. The thickness of the refractory lining for the end walls will be regulated 55 in accordance with the insulation required, because the greater the heat the more the slag will fill the compartments 43 before it becomes solidified.

Obviously those skilled in the art may 60 make various changes in the details and arrangement of parts without departing from the spirit and scope of my invention as defined by the claims, and I desire, therefore, not to be restricted to the precise construction herein disclosed.

I claim:—

1. A furnace comprising metallic walls; a lining made up of hollow blocks fitted closely together; and perforated partitions in the blocks dividing the interior of the latter into cells which are in communication with each other through the perforations of said walls. 70

2. A furnace comprising perforated metallic walls; a lining of hollow blocks fitted closely together and secured to said walls; and perforated partitions in the blocks dividing the latter into cells, there being unobstructed communication between the cells of each block and the outside atmosphere through the perforations of said walls and said partitions. 75 80

3. The combination of a furnace, and a plurality of hollow metallic blocks connected to a plurality of flat surfaces on the interior of said furnace and having their adjacent edges resting closely together. 85

4. A furnace comprising perforated metallic walls; a lining made up of hollow blocks secured to said wall, the sides of the blocks adjacent said walls being open affording communication between the interior of each block and the outside atmosphere through the perforations of said wall; and a perforated partition in each block substantially parallel with the outside wall adjacent such block dividing the block into cells with communication between the cells through the perforations of said partition. 90 95

5. A furnace comprising inclosing walls, 100 and a hollow continuous metallic lining locked to the inner sides of said walls.

6. A furnace comprising a plurality of hollow blocks having adjacent edges fitting closely together, and dovetail connections between said blocks and the inner surface of said furnace to form a continuous lining. 105

7. A furnace comprising an uninterrupted cellular lining, and means for locking said lining to the inner surface of said 110 furnace.

8. A furnace comprising cellular inclosing walls, the inner surfaces being of metal and initially sealed from the interior of said furnace, said walls being directly in communication with the outside atmosphere at a multiplicity of points. 115

9. A furnace comprising a cellular inclosure and perforated partitions between the cells of said inclosure. 120

10. A furnace comprising a plurality of flat inclosing walls, a plurality of hollow blocks secured to the inner surface of each wall to form a continuous lining for the furnace, and means dividing the interior of each block into cells. 125

11. A furnace comprising a plurality of flat inclosing walls, a set of hollow blocks for the interior surface of each wall, each set comprising a plurality of said blocks, 130

- transverse dovetail grooves on the inner surfaces of said walls, locking extensions on said blocks fitting in said grooves, and a perforated partition in each of said blocks 5 to form small compartments in communication with the outside atmosphere through perforations in the bottom of each block and perforations through said walls.
12. A furnace having a lining composed 10 of a plurality of hollow blocks each closed to the interior of the furnace and each in communication with the outside atmosphere.
13. A furnace comprising a cellular in- 15 closure closed to the interior of the furnace and in communication with the outside atmosphere in a multiplicity of places.
14. A furnace comprising perforated in- 20 closing walls, a lining composed of a plurality of hollow blocks for each interior surface of said walls, each block being closed where exposed to the interior of the furnace and open on the opposite side, and integral perforated partitions in the blocks 25 affording communication between the interior of said blocks and the outside air through said perforated walls.
15. A furnace comprising perforated metal inclosing walls, hollow metallic lining 30 blocks secured to the inner sides of said walls, and foraminous partitions dividing the interiors of said blocks into small compartments providing communication between the interior of said blocks and the outside atmosphere. 35
16. A furnace comprising a cellular in- 40 closure closed to the interior of the furnace but in communication with the outside atmosphere, the inner surfaces of said inclosure being of metal and adapted to be melted to cause molten slag to enter said cells and be chilled by the air to form a refractory lining for said furnace.
17. A furnace comprising perforated in- 45 closing walls, and a lining of hollow metal blocks secured to the inner sides of said walls, said hollow blocks being adapted to receive molten material from the interior of the furnace to be cooled by air passing 50 through the perforations of said walls into
- said hollow blocks to form a refractory lining for said furnace.
18. A furnace comprising perforated in- 55 closing walls, a lining of hollow iron blocks secured to the inner sides of said walls, and a perforated partition in each hollow block to divide the latter into small compartments.
19. A furnace comprising a perforated in- 60 closure and a cellular iron lining for said inclosure comprising perforated partitions affording communication between said cells and the outside atmosphere.
20. A furnace comprising four flat perforated inclosing walls, a cellular lining of 65 iron comprising a plurality of hollow blocks secured to the inner surface of each inclosing wall, and perforated partitions establishing communication between the cells and the outside atmosphere, said lining being 70 closed to the interior until partially melted away and slag partially fills the cells and becomes chilled by the outside atmosphere to form a refractory lining for the furnace.
21. A furnace comprising cellular inclosing walls adapted to receive molten material 75 from the interior of said furnace to be chilled by the outside atmosphere through exterior openings communicating with said cells to form a refractory lining for said furnace. 80
22. A furnace comprising a perforated in- 85 closure, means comprising perforated partitions for forming a plurality of air cells in communication with the outside atmosphere through said perforated inclosure, and means for initially sealing said air cells from the interior of said furnace but adapted to be melted away to cause the slag in the furnace to enter said air cells and become chilled to form a reinforced refractory lining for said furnace. 90
